UNITED STATES PATENT OFFICE.

GOTTLIEB HEIDMANN, EMIL HÖTTGES, AND CARL EGEN, OF BARMEN, PRUSSIA, GERMANY, ASSIGNORS TO HEIDMANN & HÖTTGES, OF SAME PLACE.

BUTTON.

SPECIFICATION forming part of Letters Patent No. 400,337, dated March 26, 1889.

Application filed September 5, 1887. Serial No. 248,870. (No model.)

To all whom it may concern:

Be it known that we, GOTTLIEB HEIDMANN, merchant, subject of the King of Prussia, residing at Barmen, 93 Alleestrasse, Prussia, 5 Germany, and EMIL HÖTTGES, merchant, subject of the King of Prussia, residing at Barmen, 32 Haspelerstrasse, Prussia, Germany, and CARL EGEN, mechanist, subject of the King of Prussia, residing at Barmen, 10 Ober-10 dörnerstrasse, Prussia, Germany, have invented certain new and useful Improvements in Buttons; and we do hereby declare the following to be a full, clear, and exact description of the invention, such as will enable others skilled 15 in the art to which it appertains to make and use the same, reference being had to the accompanying drawings, and to letters or figures of reference marked thereon, which form a part of this specification.

20 Referring to the drawings, Figure 1 is a top plan view of our improved button without the covering. Fig. 2 is a vertical transverse section thereof. Figs. 3 and 4 are like views showing the mode of covering the button. 25 Fig. 5 is a view similar to Fig. 2, showing a modified construction.

The invention relates to what is known as cloth-covered buttons, and these are usually constructed of two or more parts irrespective 30 of the covering and cloth shank, more generally of two parts—namely, a button head or disk and a retaining or back plate for securing the shank to the disk, the cloth cover being usually secured by bending or upsetting 35 the edge of the button head or disk over the edge of the back-plate and cover to secure the parts of the button together. It has become the practice to furnish the several parts 40 of cloth-covered buttons to consumers to enable them to select the covering therefor, the button being completed by the consumer by well-known hand-machines, the operation of uniting the several parts requiring some care and attention. In uniting the several parts 45 of such a button they are separately and successively introduced into the machine and united in a well-known manner. If, however, the parts are not properly placed in position, either the cover for the button is not perfectly 50 secured or, as it very often happens, the button is destroyed by being bent out of shape.

The object of this invention is to provide a button the parts of which, except the covering, are already united, and that will require in the application of the cover the upsetting 55 of one of the parts only, so as to avoid the losses and inconveniences above referred to, and also to materially simplify the operation of covering the buttons. The button being complete, with the exception of the cover and 60 the parts thereof secured together, the mere upsetting of one of the said parts is, in fact, simply a change in form of the button-frame. The machines by means of which this change of form is effected are therefore of the very 65 simplest construction.

To these ends the invention consists in a button-frame as an article of manufacture, substantially as hereinafter described, and as set forth in the claims.

70 Our improved button-frame consists of the usual head or disk, *a*, a cloth shank, *d*, and back or retaining plate, which is of peculiar construction. This back-plate may be made in two sections, *b* and *f*, if desired; or it may 75 be made of one piece. In the drawings we have shown said plate of two sections—namely, the back-plate *b* proper, provided with tubular extension *b'*, and a cover-retaining plate, *f*, provided with a flaring or dished upper end, 80 *f'*, and a tubular extension, *f''*, provided with a seat-flange, *f'''*. As shown, the sleeve or tubular extension *f''* of the cover-retaining plate *f* encompasses the cloth shank *d* and serves as a bearing for the back-plate *b*, that holds the 85 cloth shank in position on the disk or head *a*, the edge of which is bent over the edge of said back-plate in the usual manner, as shown in Figs. 1 and 2. The dimension of the flaring or dished portion *f'* of the cover-retaining 90 plate *f* relatively to the dimension of the back of the button inside of the bent edge of the button-head is such as to admit of the cover *h* being readily applied to the button and folded over the bent edge thereof by the following B, as shown in Figs. 3 and 4, and so as to avoid all liability of displacement during the operation of covering. The latter operation is one very simple. The cloth disk *h* being laid in its place in the machine with the 95 button-frame thereon, the follower is depressed, the follower B first folding the cloth 100

cover over the back of the button, when its further downward motion is arrested. The follower D, next coming in contact with the dished or flaring portion f' of the cloth-retaining plate, upsets the same upon the cloth, the edge of said plate and the cloth cover being forced under (or approximately so) the bent edge of the button-head, the parts being thus securely fastened together.

10 There is, as described, but one operation in the completion or covering of the button, and, if desired, the flaring or dished portion f' of plate f may have a toothed or serrated edge to better hold the cloth cover.

15 Having described our invention, what we claim is—

1. As an improved article of manufacture, a blank for cloth-covered buttons, consisting of a button head or disk provided with an upturned peripheral flange, a cloth shank, and a dished or outwardly-flaring cloth-retaining plate, f , said parts being permanently assembled for the reception of the cloth cover, substantially as described.

25 2. As an improved article of manufacture,

a button-frame for cloth-covered buttons, comprising the herein-described button head or disk, a cloth shank, a shank-retaining plate, and a cloth-cover-retaining plate, said parts being all united together, as described, and ready for the reception and securing thereto of the cloth covering through the medium of the cover-retaining plate, substantially as and for the purpose specified.

3. The herein-described button-frame, consisting of a button head or disk, a cloth shank, and a shank-retaining plate secured to the disk by upsetting the edges thereof over the edges of said plate, in combination with the dished or flaring cover-retaining plate or disk f' , connected with the other elements of the button-frame, substantially as described.

In testimony whereof we affix our signatures in presence of two witnesses.

GOTTLIEB HEIDMANN.
EMIL HÖTTGES.
CARL EGEN.
